S. B. EGAN

ADVERTISING DEVICE

Filed Nov. 21, 1924

INVENTOR
SIDNEY B. EGAN

By Henry P. Bloyd ATTY

UNITED STATES PATENT OFFICE.

SIDNEY B. EGAN, OF OAK PARK, ILLINOIS.

ADVERTISING DEVICE.

Application filed November 21, 1924. Serial No. 751,275.

To all whom it may concern:

Be it known that I, SIDNEY B. EGAN, a citizen of the United States, residing at 211 Linden Avenue, Oak Park, in the county of Cook and State of Illinois, have invented new and useful Improvements in Advertising Devices, of which the following is a specification.

The present invention relates to advertising devices and has to do particularly with a device adapted to be used with a plurality of interchangeable advertising cards or inserts.

Among the objects of the invention are the following:

The provision of a novel blank for forming a card supporting means, the folding of such a blank to provide for two inserts, one to be in the foreground and the other to provide the background thereof;

The correlation of the various elements which constitute the device in such a manner that the greatest economy in stock is secured in its production; and

The formation from pasteboard or similar material of an advertising novelty having a design giving a stage effect, the foreground and background being adapted to be changed at will.

These, and such other objects as may hereinafter appear, are attained by the novel construction, combination and arrangement of the various elements which constitute the invention, one sheet of drawing being attached hereto and made a part of this specification for the purpose of illustrating the invention.

Figure 1 in said drawing is a plan view of a blank for forming one embodiment of the invention.

Figure 2 is a front view of such embodiment.

Figure 3 is a top view of the device taken on the line 3—3 of Figure 2 and looking in the direction of the arrows.

Figure 4 is a vertical section through the device taken on the line 4—4 of Figure 2 and looking in the direction of the arrows.

Figure 5 is a plan view of a blank for forming a second embodiment of the invention.

Figure 6 is a top view of said second embodiment of the invention.

Like reference characters are used to designate similar parts of the several figures

and in the description of the invention which follows.

In present day point of purchase advertising practice, there is a growing tendency to coordinate advertising efforts into what is called a service, where at stated and regular intervals, seasonable advertising material is supplied to retail establishments for display. While some advertisers mail regularly complete new sets of advertising material, considerable merit has been found in furnishing to a retailer a holder or stand provided with means for receiving material comprising cards, inserts or the like for the time being, such material to be replaced from time to time with new material, the changes to occur as such new material is received by the retailer.

Holders or stands of a permanent nature have been proposed but these are costly to manufacture and transport, and many of these find their way into the waste before they have earned their cost in advertising value. In many establishments, there is an aversion to anything in advertising which savors of permanency, and it is a fact that many chain store systems have instructed their store managers to refuse to receive or display any advertising material which, by its nature, is of such a fixed character that it is cumbersome and not readily removable and easily destroyed.

For overcoming these objections, and other objections to changeable point of purchase advertising, the present invention was conceived. It presents in a holder or stand a structure as efficient as expensive permanent devices, with costs saved in material, manufacture, and distribution. It has greater mobility, a wider range of usefulness, and because of its novelty, has the added asset of arousing attention.

Reference should now be had to the drawing submitted herewith. In Figure 1, a blank 10 of cardboard or similar material is disclosed. This blank may be cut from sheet material at a single die cutting operation for it comprises a plurality of simple angles and straight scores.

From blank 10, the holder or "stage" is formed by articulating the various parts and extension portions thereof and interlocking two of said parts.

That these several parts may be identified, that portion of blank 10 providing the front

of the set-up device is designated 11, and the section forming the back thereof 12. Out of the front 11 is cut an aperture or opening 13, the purpose of which will 5 shortly be apparent. Front section 11 may have an integral extension portion 14 upon its top margin for decorative purposes as indicated.

Intermediate the front section 11 and 10 back section 12 is a vertical score 15 to facilitate articulation, and at the end opposite that to which the back section 12 is joined, a short section 16 separated from front section 11 by a score 17 is provided, 15 said score 17 being parallel to score 15 and providing for ready articulation of said section 16.

Depending from the lower edge of each 20 of sections 11, 12 and 16 are short extension portions, separated one from another by the removal of a small portion of the material intermediate said extensions. A single continuous score 18 at the lower edge 25 of sections 11, 12 and 16 separates all of said extensions from said sections and facilitates articulation.

Said short extensions from left to right are identified as follows: The extension upon 30 section 16 bears the ordinal 19, that upon front 11 is identified by the numeral 20, and the two extensions upon back section 12 are designated 21 and 22. With respect to 35 said extensions 21 and 22, it will be noted that in addition to the material therebetween being removed at their adjacent margins, the lower margins of said extensions are formed in a single arc to facilitate the folding operation now to be described.

When the blank 10 is shipped it may be 40 packed flat or it may be articulated upon the score 15 to make a shorter package. To set up, it is usual to first articulate upon the line defined by score 18. The second and 45 third articulations are made upon scores 15 and 17. A slight separation is made between section 16 and extension 19, whereupon the material of back section 12 and extension 22 are inserted therein until the 50 end margin of back 12 abuts the material of front 11 adjacent score 17. This provides a stage-like device having a flat front 11 with the extension 20 inwardly disposed and upwardly turned to receive an apertured advertising card 23 (see Figures 2 and 55 3), and a curved back with an inwardly disposed and upwardly turned card receiving section for a bent card 24, (see Figure 3), such card receiving portion comprising back section 12 and extensions 19, 21 and 22. 60 Card 23 is of substantially the same length as front 11 and ordinarily is apertured, or to be more exact, it comprises an integral border extending entirely there-around, and an object or objects in outline 65 such as the dress, hose and shoes shown in

Figure 2 are made to extend from one or more of its sides. Said card 23 is seated at its lower margin between front 11 and extension 20, and is held against backward displacement by engagement with the curved 70 wall of back 12 or by card 24. Said card 24 is of substantially the same dimension as back 12 and is printed on the surface to be exposed when said card is disposed in the seat therefor comprising the extensions 21 75 and 22 upon back 12. The arcuate margins of said extensions 21 and 22 and the removal of a portion of material therebetween facilitate the obtaining of regularity in the curve of back 12 and of said extensions 21 80 and 22 and prevent any buckling or other untoward effect, the result of an excess of material. Forward displacement of card 24 is prevented by its curved position and by the proximity of front 11 to its ends when 85 said card 24 is in proper position.

It is quite manifest that cards 23 and 24 may be removed and replaced at will, and that the device and the interchangeable cards therefor may be handily packed in a 90 flat package for shipment and easily transported at low cost from point to point. When set up, the curve in the material of back 12 and extension 22 in conjunction with that in section 16 and extension 19 95 creates considerable friction between abutting surfaces of material, rendering accidental separation between said parts almost impossible.

In Figures 5 and 6, a second blank 30 illustrating another embodiment of the invention is disclosed. In this embodiment an apertured front 31 and a back 32 are provided. The aperture in front 31, designated 33, is suggestive of an object or objects as in the case of card 23 in the previously described embodiment.

Front 31 has a top integral extension 34, and is separated from back 32 by score 35. Back 32 is printed on the side opposite to that on which front 31 is finished, for reasons that shortly will be apparent.

An extension 36 separated from front 31 by scoring 37 is provided. On the margin of said extension 37 are a plurality of tongues 38 adapted to register with and be inserted into a plurality of aligned slots 39 in the free end of back 32. As back 32 is of greater length than front 31, it is necessary to bend back section 32 to secure registration of tongues 38 and slots 39, but when the free end of back 32 is brought inside of extension 36, and said tongues 38 are seated in slots 39, a snug interfit is obtained and back 32 is securely locked against accidental separation from extension 36. Figure 6 clearly shows the bending of the material of tongues 38 as an incident to the setting-up of the device.

From the foregoing it is quite manifest

how the device operates. But two articulations are necessary in order to put it in operable position, such folding permitting of viewing the finished surface of back section 5 32 through aperture 33 in front 31.

Other forms of the device are possible and within the spirit of the invention, but it is believed that the two embodiments disclosed and described will be sufficient to illustrate the invention as set forth in the appended claims.

I claim:—

1. An advertising device possessing physical resemblance to a stage comprising a blank 15 for providing the front of said device and having extensions, one of said extensions being bent in a regular arc and being adapted to form the back of said device, said front and back having upturned extensions 20 adapted to form pockets to receive replaceable advertising matter whereby to change the character of advertising displayed in said device.

2. In an advertising device possessing physical resemblance to a stage, a blank 25 having an extension portion adapted to be articulated, part of said blank providing a

front for said stage, and the remainder thereof the background therefor, said extension portion when articulated providing 30 a pocket to receive removable inserts.

3. An advertising novelty having physical resemblance to a stage comprising an apertured blank forming the front of said stage and having extension portions, a 35 part of said extension portions being adapted to inter-lock to provide a back for said device, and another part a parallel offset wall upon the margin of said blank whereby to hold replaceable card inserts uprightly 40 in said device.

4. An advertising novelty comprising a blank forming a stage-like holder having marginal pockets to receive removable and replaceable cards adapted to provide a 45 change in the foreground and the background of said stage, said blank comprising a plurality of sections having extensions, said sections being separated by parallel 50 scores to provide the front and the back of said stage, and said extensions being separated from said sections by a single continuous score to provide said marginal pockets.

SIDNEY B. EGAN.
